UNITED STATES PATENT OFFICE.

AGNES MAJERNIK, OF MINNEAPOLIS, MINNESOTA.

LIFE-SAVING DEVICE.

1,051,143.

Specification of Letters Patent. Patented Jan. 21, 1913.

Application filed August 16, 1912. Serial No. 715,422.

To all whom it may concern:

Be it known that I, AGNES MAJERNIK, a subject of the King of Hungary, residing at Minneapolis, in the county of Hennepin and State of Minnesota, have invented certain new and useful Improvements in Life-Saving Devices, of which the following is a specification, reference being had therein to the accompanying drawing.

10 This invention relates to water wings, especially designed to facilitate teaching swimming and as a life saving device that can be used similar to an ordinary buoyant life saver ordinarily carried by large ocean going vessels.

The primary object of my invention is to provide a flexible collapsible water wing with novel means whereby it can be inflated and easily strapped to the body, in the vicinity of the shoulders of the body, whereby the upper part of the body will be maintained afloat upon water either when being taught or learning to swim or when an accident occurs that requires the use of a life saving device.

A further object of this invention is to provide a life saving device of the above type that is simple in construction, durable, easy to apply to the body and highly efficient for the purposes for which it is intended.

I attain the above objects by a mechanical construction that will be hereinafter specifically described and then claimed, and reference will now be had to the drawing, wherein:

Figure 1 is a front elevation of a water wing in accordance with this invention. Fig. 2 is a cross sectional view of the same taken on the line II—II of Fig. 1, showing the wing collapsed. Fig. 3 is a similar view of the wing inflated, and Fig. 4 is a cross sectional view of the water wings as inflated.

45 A life saving device in accordance with this invention comprises two integral wings that are generally designated 1. The wings are made of two pieces of flexible water-

proof material, as silk rubber and one piece of material forms a straight rear wall 2. 50 This rear wall is capable of being collapsed, as shown in Fig. 2 and the other piece of material has the edges thereof stitched or otherwise connected to the wall 2, as at 3. The last mentioned piece of material has 55 an intermediate neck portion 4 providing a filling compartment and the other compartments of the device are substantially oval in cross section, when inflated, as shown in Fig. 3. The wings 1 have the 60 front sides thereof curved and said wings are of a sufficient size to provide bodies that are buoyant when said bodies are inflated. This is accomplished by providing the neck 4 with a flexible filling tube 5 and air can 65 be blown or pumped into the neck 4 to inflate the wings 1. The tube 5 can be tied with a piece of cord or otherwise closed to retain the air within the wings 1. The neck 4 of the life saving device has a tab 6 and 70 stitched or otherwise connected to said tab, as at 7 is a strap 8, one end of said strap having a button 9 and the other end a button hole 10, said button and button hole constituting means whereby the strap 8 can 75 be fastened around the body, adjacent to the arm pits, whereby the life saving device will be supported upon the back in proximity to the shoulder blades or neck.

The life saving device when collapsed 80 can be folded and readily carried in the pocket, and when inflated with air, the wings 1 present sufficient area upon the surface of water to support a body.

What I claim is:

85 A life saving device comprising a pair of oppositely disposed inflatable wings substantially oval-shaped in cross section and gradually increasing in area toward each terminus, the forward wall of each wing 90 being rounded and the rear wall substantially straight in vertical section, said rear wall capable of being folded toward the front wall upon itself when the wings are deflated, an oval-shaped neck portion of the 95 same area throughout merging in the inner

terminus of each of said wings, a flexible
filling tube communicating with said neck
portion, a rectangular tab secured to the
rear of said neck portion, and a strap fixedly
secured to the upper face of said tab and
adapted to secure the device to the body of
a person.

In testimony whereof I affix my signature
in the presence of two witnesses.

AGNES MAJERNIK.
